CHICK GUARD FOR BROODERS

Haydn G. Basinger, Toledo, Ohio

Application April 12, 1926. Serial No. 269,566

1 Claim. (Cl. 119—32)

This invention relates to a guard for use in connection with brooders to prevent the piling and smothering of very young chickens or chicks in an endeavor to position themselves relatively to the stove.

It is particularly aimed to provide a construction whereby a number of the guards coact about a heater so as to house a predetermined number of the chicks and insure movement thereof toward and away from the stove and which will avoid housing such a number as will pile upon each other so as to cause smothering and injury.

The more specific objects and advantages will become apparent from a consideration of the description following taken in connection with accompanying drawing illustrating an operative embodiment.

In said drawing:—

Figure 1 is a perspective view of a brooder equipped with my improvement;

Figure 2 is a plan view illustrating my improved guards arranged about a brooder stove, the latter being suggested in dotted lines;

Figure 3 is a detail sectional view taken on the line 3—3 of Figure 2, and

Figure 4 is a detail sectional view taken on the line 4—4 of Figure 2.

Referring specifically to the drawing wherein like reference characters designate like or similar parts, the brooder is of the type having a central stove or heating element as at 10 and is arranged centrally of and so as to support a canopy at 11, beneath which the chicks are adapted to hover or brood.

In carrying out my invention, any suitable number and sized guard sections are provided as at 12 and for instance four in number. Such sections are generally segmental and each may consist of three radial walls, being outer walls 13 and a central or partition wall 14. Such walls are held together at the top by means of any desired number of braces 15 having terminal depending lugs 16 through which removable bolts 17 are passed and which also pass through the walls 13 and 14. Braces at 18, similar to those at 15 are bolted at 19 to the walls 13 and 14. Such walls 13 and 14 and braces may be made of any material desired, for instance imperforate metal, wire fabric, pasteboard or otherwise. In addition, they may be fastened together in any suitable way and no limitation therefor to the bolts 17 and 19 is to be implied and further the number of braces may also be altered.

All of the parts of the guards 12 except the bolts or fastening elements are for instance con-

structed of galvanized sheet metal although no limitation in this regard is to be implied since they may be made of wood, pasteboard or other material if preferred and according to conditions.

In using the device, instead of the chicks overcrowding and lodging too closely together, and pushing each other from all directions, and causing smothering and injury, the guards may be so arranged as to house a predetermined number of the chicks and such a number relative to its size that the crowding and pushing cannot occur with injurious effects. As far as possible, the number of chicks housed by each guard is the same.

In the drawing the outer or vertical wall of the brooder has been omitted for the sake of clearness. While the walls 13 and 14 may be made of netting or open material, it is preferred to make them imperforate as shown so as to shield the chicks from draft, which cannot be avoided in many constructions of brooder houses.

The guards are independent of each other and therefore may be readily adjusted and arranged in brooder houses of various sizes, may be compactly arranged during shipment and are of such a construction that the chicks may move toward or away from the stove 10 in adapting themselves to the proper degree of heat, and in the case of an overheated stove, the chicks are at freedom to move as far as they wish away from the stove 10.

Various changes may be resorted to provided they fall within the spirit and scope of the invention.

I claim as my invention:—

In combination with a brooder stove and a canopy above the same, a guard to house chicks, said guard having vertical walls arranged in substantially radial relation to said stove, said guard being disposed substantially completely beneath the canopy, connecting elements for said walls in spaced relation at the top thereof arranged in pairs substantially concentric with the stove, said elements having depending lugs, and fastening elements securing the connecting elements and walls together, the spaces between the vertical walls being substantially unobstructed below said elements.

HAYDN G. BASINGER.
